[57] **CLAIM**

The ornamental design for an electronic computer, as shown and described.

DESCRIPTION

FIG. 1 is a top, front and right side perspective view of an electronic computer showing my new design;

FIG. 2 is a front elevational view thereof;

FIG. 3 is a top plan view thereof;

FIG. 4 is a left side elevational view thereof;

FIG. 5 is a right side elevational view thereof;

FIG. 6 is a rear elevational view thereof;

FIG. 7 is a bottom plan view thereof;

FIG. 8 is a top plan view thereof in a closed position;

FIG. 9 is a front elevational view thereof in a closed position;

FIG. 10 is a right side elevational view thereof in a closed position;

FIG. 11 is a top plan view thereof with the keyboard being moved to a middle position; and,

FIG. 12 is a top plan view thereof with the keyboard in another position.
